DESIGN FOR A FINGER RING

Otto H. Mengel, Newark, N. J., assignor to Acme Ring Co., Newark, N. J., a corporation of New Jersey

Application April 12, 1937, Serial No. 68,680

Term of patent 3½ years

To all whom it may concern:

Be it known that I, Otto H. Mengel, a citizen of the United States and a resident of Newark, in the county of Essex and State of New Jersey, have invented a new, original, and ornamental Design for a Finger Ring, of which the following is a specification, reference being had to the accompanying drawing, forming part thereof.

Figure 1 is a top plan view of a finger ring showing my new design.

Figure 2 is a side elevational view of the ring. Figure 3 is an elevational view of one end of the ring, and

Figure 4 is an elevational view of the other end thereof.

I claim:

The ornamental design for a finger ring as shown.

OTTO H. MENDEL.
